UNITED STATES PATENT OFFICE.

WILLIAM THAD MARGASON, OF MARYVILLE, TENNESSEE.

OIL BURNER.

Application filed July 12, 1927. Serial No. 205,096.

This invention relates to oil burners of the gravity feed type and is adapted particularly for burning heavy flowing oils such as crude oil, fuel oil or the oil drained from 5 the crank cases of automobiles or other cheap forms of liquid fuel.

An object of the invention is to provide a base having an oil pan formed therein and having the burner mounted above the base 10 and arranged with respect thereto whereby to form an air draft between the base and the burner whereby to facilitate the operation of the device.

A further object is to form a drip flange 15 about the burner and in a position to direct the overflow from the orifices formed in the burner whereby to deposit any excess of oil to the drip pan.

Another object is to provide an article of 20 this character of simple and practical construction, efficient and reliable in performance, economical in consumption of fuel, and adapted to use fuels of a cheap grade, inexpensive to manufacture, and otherwise well 25 adapted for the purposes for which the same is intended.

Other objects and advantages reside in the special construction and combination of the various elements forming the invention, reference being had to the accompanying drawings forming a part hereof, wherein:—

Figure 1 is a perspective view of one type of burner in assembled position.

Figure 2 is a vertical transverse sectional view therethrough.

Figure 3 is a longitudinal sectional view therethrough.

Figure 4 is a fragmentary bottom plan view illustrating the manner in which the 40 air draft space is formed between the walls of the base and the oil pan.

Figure 5 is a vertical transverse sectional view through a circular type of burner.

Figure 6 is a top plan view thereof.

Figure 7 is a horizontal sectional view through the base of the circular burner, and,

Figure 8 is a detail showing the attaching means between the base and the burner.

Referring now to the drawings I have disclosed my invention comprising a base indicated at 5 which may be of a rectangular construction as shown in Figures 1 to 4 inclusive, or which may be of an annular construction as illustrated in Figures 5 to 7 inclusive. An oil pan 6 is formed within

the base having its bottom section spaced above the lower edge of the base whereby to form an air space beneath the pan, one of the vertical walls 7 of the pan being spaced in parallel relation from one of the 60 walls of the base 5 whereby to form a vertical air passage communicating with the air space beneath the pan tending to cause an air draft for moving upwardly between the wall 7 of the pan and the side of the base. 65 A bridge 8 communicates between the wall 7 and the side of the pan 5 to form a support for the pan.

The pan 6 and air space between the wall 7 thereof and the base 5 opens upwardly and 70 the upper edge of the base is adapted to support a burner 9 disposed along one side thereof, the supporting edges of the base and the burner being arranged in overlapping relation as indicated at 10 to form a 75 tight fit therebetween and at each outer side of the base and the burner I provide ears 11 forming means for securely attaching the parts in position.

The front end of the burner 12 is suspended 80 above the pan 6 and is disposed slightly below the upper edge of the base. Between the rear edge of the burner and the front edge 12 thereof is formed an upwardly extending air pocket 13 communicating with the air space between the vertical wall 7 of the pan and the wall of the base and arranged to direct the air draft passing therethrough downwardly into the pan 6.

The inner end of the burner 12 is provided 85 with a longitudinally extending oil feed passage 14 having a threaded opening at one end whereby to attach an oil feed pipe and having a cleanout plug 15 formed in its opposite end. A plurality of orifices 95 16 extend through the wall of the burner from the feed passage 14, nipples 17 being formed about said orifices arranged on the upper surface of the inner end of the burner 12. Flanges 18 are arranged at 100 each end of the inner edge 12 of the burner to direct any overflow of oil from the burner into the pan and prevent the same from dripping.

Shields 19 are also formed at each side of 105 the burner 12 to prevent oil from dripping over the side edges thereof.

In the construction of the burner in a circular form, a slight modification of the several parts is found necessary, in such in- 110

stance the vertical walls 20 of the oil pan 21 are spaced from the wall of the base and supported in spaced relation by bridge members 22. As shown in Figure 5 of the drawing, the bottom of the pan is supported above the lower edge of the base 5. This construction provides for an air space beneath the pan communicating with the air space between the walls of the base and the pan. The annular burner 23 in this construction is provided with an annular oil passage 24 connecting with an oil feed pipe 25, the upper edge of the burner being inclined inwardly toward the center of the pan as likewise is the case with respect to the rectangular burner, the inclined surface of the burner being provided with orifices 26 having nipples 27 formed thereabout and communicating with the oil passage 24. The inner edge of the burner extends inwardly over the oil pan 21 and has a downwardly extending flange 28 formed about its lower inner edge. The flange thus comprises a drip for any excess of oil discharged through the orifices and which is not consumed during the operation of the burner, thereby depositing the same into the pan 21.

The quantity of fibre asbestos indicated at 29 may be placed within the pans 6 and 21, which after being saturated with the oil may be ignited so as to heat the inner edge of the oil burner extending over the pan thereby tending to create a gas from the oil within the oil passages which upon being discharged through the orifices together with the overflow of oil therefrom will become ignited from the flame within the pan. The air draft directed against the inner edge of the burner by the burning of the oil

within the pan will intensify the burning of the gas and oil from the burner.

It is obvious that the invention is susceptible of various changes in shape, size and form, without departing from the spirit or scope of the appended claims, and I accordingly claim all such forms of the device to which I am entitled.

I claim:—

1. In a device of the class described, a base, an oil pan supported within the base above the lower edge of said base with the wall of the pan and the base arranged in spaced relation to form an air passage communicating with the air space beneath the pan, a burner arranged upon the upper edge of the base having one edge extending inwardly over the pan, an oil passage formed in the burner extending throughout its area, orifices communicating therewith and a drip flange carried at the inner edge of the burner and suspended above said pan.

2. In a device of the class described, a base, an oil pan arranged within the same and supported above the lower edge of the base with the walls of the pans spaced from the walls of the base whereby to form an air passage opening upwardly from the base and the pan, a burner supported upon the upper edge of the base with its inner edge extending over the pan and having an oil passage formed therein, orifices arranged in the upper surface of the burner communicating with said passage, said orifices having nipples formed thereabout and a flange arranged on the lower inner edge of said burner.

In testimony whereof I affix my signature.

WILLIAM THAD MARGASON
